(57) **CLAIM**

The ornamental design for an air conditioner as shown and described.

DESCRIPTION

1. Air conditioner
- 1.1 : Perspective
- 1.2 : Front
- 1.3 : Back
- 1.4 : Left
- 1.5 : Right
- 1.6 : Top
- 1.7 : Bottom
- 1.8 : Enlarged

The broken lines depict portions of the air conditioner that form no part of the claimed design; this design is for an air conditioner which can make stable wind with the grilles on both sides; reproduction 1.8 is a partial enlarged view of the area '1.8' as identified in reproduction 1.1.

1 Claim, 8 Drawing Sheets
